UNITED STATES PATENT OFFICE.

FRANK J. SCHROEDER, OF ALTOONA, PENNSYLVANIA, ASSIGNOR TO NORMAN E. GEE,
OF ALTOONA, PENNSYLVANIA.

PNEUMATIC HAMMER.

1,230,802.

Specification of Letters Patent. Patented June 19, 1917.

Application filed April 8, 1915. Serial No. 20,080.

To all whom it may concern:

Be it known that FRANK J. SCHROEDER, a citizen of the United States, residing at Altoona, in the county of Blair and State 5 of Pennsylvania, has invented certain new and useful Improvements in Pneumatic Hammers, of which the following is a specification.

This invention relates to an improvement 10 in pneumatic hammers, and has particular reference to a novel tool retainer therefor.

In connection with the use of pneumatic hammers, it is well known that if the trigger is accidentally pressed when the tool is 15 not held up to its work, that the tool is discharged with the force of a projectile from a gun, and within a comparatively close range may have a deadly effect. Accordingly, the present invention contemplates a 20 safety construction for pneumatic hammers which will effectively lock the tool in place or restrain the same within the barrel, though at the same time permitting it to exercise its normal functions when in use.

25 Primarily the invention has in view a plurality of segmental tool engaging and locking plates which restrain or prevent the tool from being shot from the barrel of a hammer, and which are held in place by a 30 single holding element that may be easily manipulated to either lock the segments in position or remove the same for replacing or reversing. In this latter connection, the invention provides a plurality of button set 35 locking elements which are readily interchangeable and reversible to present fresh unworn surfaces. That is to say, the present type of locking elements involve opposite flat surfaces one of which is subjected to the 40 continuous intermittent impact of a shoulder on the tool, due to the piston subjecting the latter to the usual hammer blow. This face of the segment will naturally wear down, while the opposite surface is fresh and 45 unworn. Thus by merely reversing the position of the segments a new surface may be presented.

Another object of the invention is to provide a construction which will not add any 50 appreciable extra weight or bulk to the barrel of the hammer, thus permitting the operator to easily manipulate the tool in close quarters, such as are often encountered in

the construction of modern steel cars, steamships, and structural iron buildings. In connection with this feature of the invention, 55 the same proposes to countersink the holding or clamping means for the locking segments so that the same will not be in the way under any condition of use of the tool.

60 A further object of the invention is to provide a novel tool or button set lock possessing strength and rigidity, and which will so lock or restrain the tool in place that it will be impossible to manually withdraw 65 the tool, that is pull or slide the same out of the barrel, without removing the locking segments, thus eliminating any possibility of the tool being accidentally discharged, as may be the case where the tool 70 is held in the barrel by yielding, holding, or retaining means.

A still further object of the invention is to provide simple and practical safety locking elements that may be economically 75 manufactured, and made in a uniform and standard size, thus facilitating their application to hammers now in use, and enhancing their value in connection with newly constructed hammers, because they are readily reversible and interchangeable. 80

With the above and other objects in view which will more readily appear as the nature of the invention is better understood, the same consists in the novel construction, 85 combination and arrangement of parts hereinafter more fully described, illustrated and claimed.

A preferred and practical embodiment of the invention is illustrated in the accompanying drawings, in which—

Fig. 1 is a plan view of a pneumatic hammer showing my invention applied thereto.

Fig. 2 is an enlarged detail view of the 95 tool head or button set showing the improved locking means applied thereto.

Fig. 3 is a cross sectional view on the line 3—3 of Fig. 1.

Fig. 4 is a side elevation of the resilient 100 locking element for holding the locking keys in position.

Fig. 5 is a front elevation of one of the reversible and interchangeable locking keys.

Fig. 6 is a bottom plan view of the key 105 shown in Fig. 5.

Fig. 7 is an end view of one of the locking keys.

Similar reference characters designate corresponding parts throughout the several figures of the drawings.

In carrying out the invention, it is proposed to utilize the same in connection with standard types and designs of pneumatic hammers, and owing to the simplicity of the safety locking elements employed in connection with the present construction, the invention may be easily adapted to hammers now in use and not equipped with a safety device for restraining the tool head.

By reference to the several figures of the accompanying drawings, it will be observed that the reference numeral 1 designates the piston barrel of the pneumatic hammer designated generally by the reference character H, while the numeral 2 designates the tool head or button set slidably arranged in one end of the piston barrel. This tool head 2 preferably includes a reduced shank portion 3 having an annular keeper recess 4 which provides an abutment shoulder 5 that is adapted to be engaged by one of the locking elements or keys generally referred to as 6.

30 In order to equip the barrel 1 for receiving and properly positioning and holding the keys 6, the same is preferably formed at one end with an annular countersunk clamp-receiving groove 7 whose opposite 35 side edges 8 and 9 are beveled as clearly shown in Fig. 1 to facilitate the application of the holding element 10 for the locking keys, hereinafter more fully referred to. The said groove 7 is provided preferably 40 at diametrically opposite points, with segmental key receiving sockets 11 which are provided with a bottom opening 12 communicating with the interior of the piston barrel 1.

45 With particular reference to the locking keys 6, which interlock with the tool head 2 to restrain the movements thereof, it will be observed that the same are of substantially flat formation, and include an elliptical head portion 13 carrying a depending keeper shank or tenon 14 which constitutes a stop or abutment to prevent the tool head from being discharged from the barrel. This type of locking key is particularly advantageous since it provides opposite wear faces 15 and 16 on the keeper shank 14, thus rendering the key capable of being reversed, and thereby insuring greater wear and longer life therefor. The bottom edge 17 50 of the keeper shank 14 is arched or curved so as to be capable of slidably fitting over the portion of the shank 3 within the keeper recess 4, as will be apparent from Fig. 3.

60 From the foregoing description, it will be evident that the barrel 1 of the pneumatic

tool H is formed with key receiving sockets 11 which are adapted to receive the reversible and interchangeable keys 6 in such a manner that the depending keeper shank 14 thereof passes through the bottom opening 12 of the socket to engage within the angular keeper recess 4 on the tool shank 3. When the keys 6 are thus in position, they are locked against displacement by means of the spring retaining ring 10 which fits flushly in the groove 7 so as to be entirely out of the way and not hinder the manipulation of the tool in close quarters. For the purpose of facilitating the manipulation of this retaining ring 10, the adjacent free end portions 19 are bent upwardly to constitute finger grips, thus enabling the operator to easily shift the ring over the beveled side 9 of the groove 7 onto the external surface of the barrel 1 when it is desired to effect a removal of the locking keys.

The particular construction at the end of the barrel 1 also materially facilitates the assembling and taking apart of the several parts constituting the present safety construction. That is to say, after the locking keys 6 are placed in position in their respective key sockets 11, the spring-retaining ring 10 may be easily slipped over the beveled edge 18 and snapped into the groove 7 after having passed over the beveled edge 8. When it is desired to remove the keys 6 for the purpose of changing tools, replacing keys or reversing the same, it is only necessary to grasp the ring 10 so that it may be shifted onto the exterior surface of the barrel over the beveled edge 9.

With regard to the keys 6, and their reversibility, it will be apparent that this feature of the invention is of much importance from a practical standpoint. When the keys are in normal locking or tool-head restraining position, the rear face 16, for instance, of the shank portion 14 is exposed 105 to the continuous intermittent impact of the shoulder 5 of the tool head, due to the latter being subject to the usual hammer blow by the piston within the barrel 1. In a short time, the face of the shank portion of the key thus exposed will become worn, while the opposite face 15, for instance, is fresh and entirely unworn. Thus, by simply removing the ring 10 and reversing the position of the key, a fresh unworn face may be 110 presented to the shoulder 5 of the tool-head shank. These keys 6 are not only reversible, but because of their novel design and construction at the end of the piston barrel 1, they are readily interchangeable, thus presenting another feature of practical importance.

Without further description, it is thought that the various features and advantages of the present invention will be readily ap- 130

parent, and it will of course be understood that minor details of construction may be resorted to without departing from the spirit of the invention or scope of the appended claims.

5 I claim:

1. A pneumatic hammer including a barrel provided with radially arranged key receiving openings of rectangular cross section and having their long diameter arranged at right angles to the axis of the barrel, said openings also being of a flaring form producing opposite seating faces, a tool-head having a stem formed with spaced apart 10 shoulders, interchangeable and reversible keys of rectangular cross section and having similar flat wear faces upon both sides, and also having opposite shoulder portions engaging said seating faces and locking tenons 15 extending through the key receiving openings into the space between the shoulders on 20

the tool-head stem, and retaining means for holding said keys in position.

2. A pneumatic hammer including a barrel having angular key receiving openings of 25 flaring form producing opposite seating faces, a tool-head having a shank formed with spaced apart shoulders, interchangeable and reversible locking keys each comprising a segmental head portion and a depending keeper shank of rectangular cross section for extending through the key receiving openings into the space between the shoulders on the tool head stem, and means for holding the said keys in position. 30 35

In testimony whereof I affix my signature in presence of two witnesses.

FRANK J. SCHROEDER.
